Manuel Jose Cuadros
By James L. Norris. M. M.

UNITED STATES PATENT OFFICE.

MANUEL JOSÉ CUADROS, OF LIEGE, BELGIUM.

METALLIC CARTRIDGE.

SPECIFICATION forming part of Letters Patent No. 444,336, dated January 6, 1891.

Application filed August 21, 1890. Serial No. 362,653. (No model.) Patented in Belgium May 28, 1890, No. 90,717.

To all whom it may concern:

Be it known that I, MANUEL JOSÉ CUADROS, military attaché, a citizen of the Republic of Peru, residing at present at Liege, Belgium, have invented certain new and useful Improvements in Metallic-Rim Cartridges and in the Means of Packeting the Same, (for which Letters Patent of Belgium, dated May 28, 1890, No. 90,717, were issued with my knowledge and consent to Mr. Joseph Penner,) and I do hereby declare that the following is a full, clear, and exact description of the invention, which will enable others skilled in the art to which it appertains to make and use the same.

Metallic-rim cartridges as at present used only allow of packets of irregular shape to be made, and these packets can generally be introduced only from one side into the magazines of fire-arms.

The object of my invention is to provide a novel construction of the cartridge-rim, whereby the cartridges can be so packed that their rims rest against each other in a rectilinear path, with the cylindrical portions of the metallic shells in superficial contact with each other throughout their length, in such manner that the cartridges can be conveniently introduced from either side into the magazine of a repeating fire-arm.

To accomplish this object my invention involves the features of construction herein-after described and claimed, reference being made to the accompanying drawings, in which—

Figure 1 is a side elevation of a cartridge embodying my invention. Fig. 2 is an end view of the same, looking at the base end of the cartridge. Fig. 3 is a side elevation of a cartridge constructed according to my invention and having parallel grooves for receiving the extractor of a fire-arm. Fig. 4 is an end view of the same, looking at the base end of the cartridge. Fig. 5 is a side elevation showing the cartridges packed in a holder. Fig. 6 is a bottom plan view of the same. Fig. 7 is a side elevation of a series of the cartridges cemented or glued together at their rims, and Fig. 8 is a bottom plan view of the same.

In the drawings, the numeral 1 indicates the cylindrical metallic shell of the cartridge, and 2 the rim at its base, which is cut away at opposite sides to form two parallel flat edges or faces 3, whereby a series of cartridges can be so arranged that the rims rest

against each other in a rectilinear path and the cylindrical portions of the metallic shells are in superficial contact throughout their length, as shown in Figs. 5 and 7. The rim of the cartridge shown in Fig. 3 is likewise cut away on two opposite sides. Moreover, at the cut-away portions opposite parallel grooves 4 are formed in the base of the cartridge-shell directly above and parallel to the opposite flat edges or faces 3 of the rim 2, which grooves are intended to be seized by the extractor of the fire-arm.

The two cartridges shown in Fig. 1 and 3 can be packed, as in Fig. 5, into a holder in such a manner that the flattened portions of the rims come in contact with each other. The packets so formed are rectangular, or nearly so, the cartridges being parallel to each other.

As a further improvement upon the foregoing, the holders can be suppressed by uniting the so-prepared cartridges by means of any suitable glue, cement, or solder. The glue, cement, solder, or other suitable substance is applied either (at 5) at the adjacent flattened portions 3 of the rims only, or also at one or more points of the cylindrical portions of the cartridge-shells.

The cartridges when packed together, either when united in a holder, as shown in Figs. 5 and 6, or when united by a cement or like substance, as in Figs. 7 and 8, are rectangular, or nearly so, in shape, and can be introduced from either side into the magazine of a repeating fire-arm.

Having now particularly described and ascertained the nature of my said invention and in what manner the same is to be performed, I declare that what I claim is—

1. A metallic cartridge-shell having its rim provided with opposite parallel flat edges or faces 3, substantially as and for the purpose described.

2. A metallic cartridge-shell having the parallel opposite grooves 4 and a rim 2, formed with opposite parallel flat edges or faces 3, directly below the parallel grooves, substantially as and for the purpose described.

In witness whereof I have hereunto signed my name, in the presence of two subscribing witnesses, this 2d day of August, 1890.

MANUEL JOSÉ CUADROS.
